Primary Examiner — Barbara Fox*(74) Attorney, Agent, or Firm* — Sterne, Kessler, Goldstein & Fox PLLC(57) **CLAIM**

The ornamental design for a portable display device with cover, as shown and described.

DESCRIPTION

FIG. 1 is a front perspective view of a portable display device with cover showing our new design, with the cover in a closed position;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the Figures show portions of the portable display device which form no part of the claimed design. The shade lines in the Figures show contour, and not surface ornamentation.
